(57) **CLAIM**

The ornamental design for an optics cup with curved bottom, as shown and described.

DESCRIPTION

FIG. 1 is a Front right side perspective view of the optics cup with curved bottom;

FIG. 2 is a front left side perspective view;

FIG. 3 is a top view thereof;

FIG. 4 is a bottom view thereof;

FIG. 5 is a view of the right-hand side of the optics cup with curved bottom;

FIG. 6 is a view of the left-hand side of the optics cup with curved bottom;

FIG. 7 is a front view;

FIG. 8 is a rear view;

FIG. 9 is a section view along lines 9-9 in FIG. 5;

FIG. 10 is a section view along lines 10-10 in FIG. 5;

FIG. 11 is a section view along lines 11-11 in FIG. 3; and, FIG. 12 is a cut-away view along lines 12-12 in FIG. 5.

The broken lines in the drawing views are included for the purpose of illustrating portions of the optics cup with curved bottom that form no part of the claimed design.

1 Claim, 10 Drawing Sheets
